UNITED STATES PATENT OFFICE.

THOMAS BRIGGS, OF LEICESTER, ENGLAND, ASSIGNOR, BY MESNE ASSIGNMENTS, TO
UNITED SHOE MACHINERY CORPORATION, OF PATERSON, NEW JERSEY, A CORPO-
RATION OF NEW JERSEY.

FASTENING-INSERTING MACHINE.

1,359,574.

Specification of Letters Patent. Patented Nov. 23, 1920.

Application filed May 21, 1917. Serial No. 169,833.

To all whom it may concern:

Be it known that I, THOMAS BRIGGS, a subject of the King of England, residing at Leicester, Leicestershire, England, have invented certain Improvements in Fastening-Inserting Machines, of which the following description, in connection with the accompanying drawings, is a specification, like reference characters on the drawings indicating like parts in the several figures.

This invention relates to machines for inserting fastenings in boots and shoes and more particularly to machines capable of inserting a plurality of fastenings successively and forming a plurality of rows of such fastenings substantially simultaneously, such machines being sometimes termed "multi-row fastening inserting machines."

For purposes of illustration the invention is herein shown as embodied in a machine of the type disclosed in United States Letters Patent No. 541,201, granted June 18, 1895, on an application of Thomas Gare, in the operation of which a plurality of individual fastenings or slugs are formed from a plurality of supplies of continuous wire and subsequently inserted simultaneously in a boot or shoe.

In the manufacture of boots and shoes it is frequently desired to insert a plurality of rows of fastenings in the soles or heels of the shoes. For example, in manufacturing or in repairing certain types of heavy boots and shoes a plurality of rows of wear resisting slugs are inserted in the shoe taps, which rows extend substantially parallel to the edge of the sole. In such work it is also frequently desired to insert one or more rows of slugs extending lengthwise of the sole, one common arrangement being to insert one or more outer rows substantially parallel to the edge of the sole and one or more inner rows extending lengthwise of the sole.

One of the objects of the present invention is to provide an improved multi-row fastening inserting machine in the operation of which the relative arrangement and location of the corresponding fastenings of the several rows, including the relative arrangement and location of the different rows, may

be varied in accordance with the particular requirements of the shoes operated upon.

In accordance with this object of the invention, the illustrated machine is so constructed and arranged that corresponding members of the several sets of operating instrumentalities are relatively adjustable in the line of feeding movement of the work. This feature enables the machine to be adapted for different relative arrangements of corresponding fasteners of the several rows, one instance of the applicability of this feature of the invention being that the machine may thus be adapted for inserting a plurality of rows so that the fastenings of the different rows will have the same relative arrangement whether the shoe be a right shoe or a left shoe; for example, so that the corresponding fastenings of the different rows may be disposed in lines more or less parallel to the break or line of demarcation between the shank and the fore-part of the shoe, the corresponding fastenings of the several rows, generally speaking, being disposed in lines substantially perpendicular to the longitudinal median line of the shoe.

In accordance with a further feature of the invention, the illustrated machine is so constructed and arranged that corresponding members of the several sets of operating instrumentalities may be relatively adjusted to cause the different rows to be inserted at varying distances apart.

Other objects and features of the invention will be apparent from the following detailed description when read in connection with the accompanying drawings and the novel features of the invention are set forth in the appended claims.

Although the invention is herein shown and described in its application to a slugging machine of the type illustrated in said Letters Patent, it is appreciated that the invention as a whole or various features thereof may have other uses, including application to slugging machines of other types.

Referring to the drawings,

Figure 1 is a perspective view of the head of a fastening inserting machine having em-

bodied therein a preferred form of the present invention;

Fig. 2 is a detail in section; and

Fig. 3 is a perspective view of the machine of Fig. 1 taken from another angle.

Machines of the type disclosed in said Letters Patent, in a machine of which type, as above stated, the present invention is herein shown as embodied, are usually provided with a plurality of wire feeding devices, each of which feeds an appropriate length of wire into a wire receiving block, relative movement between the said block and a throat member operating to sever the wire and dispose the severed length of wire in alinement with a driver for the inserting operation of the driver. The illustrated machine is provided with three such sets of instrumentalities, each comprising wire feeding means, a wire receiving and nail shearing block, a nail throat, and a driver, and the operation of the instrumentalities of each set may conveniently be effected in substantially the same manner that the operation of the corresponding devices is effected in the machine disclosed in the Letters Patent above referred to.

In accordance with the present invention, three shear blocks, 2, 4 and 6 are disposed transversely of the machine, the middle shear block 6 being not adjustable. The outside shear blocks 2 and 4 are slidably mounted for adjustment transversely of the line of feed of the work upon a stationary bracket 8 which projects horizontally from the machine frame, the blocks 2 and 4 being clamped in adjusted positions on the bracket 8 by bolts 10 and 12. The said outside blocks 2 and 4 are each provided with two wire receiving passages 14 and 16 respectively and the center block 6 with a single passage 14.

Three fastening receiving throats 18, 20 and 22 each of which is provided with a single nail and driver passage 27 are arranged to move directly beneath the shear blocks 2, 4 and 6, the center throat block 22 being not adjustable. The outside throat blocks 18 and 20 have tongue and groove connections 19 with two block carriers 24 and 26 respectively, the tongue and groove connections 19 extending in the direction of the feed of the work to enable the throat blocks 18 and 20 to be adjusted on their carriers 24 and 26 in the direction of the feed of the work, as indicated by a comparison of the full and dotted line positions of the nail passages 27 in the outside throat blocks in Figs. 1 and 2. The said throat blocks 18 and 20 are clamped in adjusted positions with the driver passages 27 therein in alinement with the drivers by clamping bolts 21.

The carriers 24 and 26 for the outside throat blocks 18 and 20 respectively are slidably mounted upon a bracket 30 which ex-

tends from the head 3 slidably mounted on the main frame 1 of the machine. In order to effect a relative conjoint or simultaneous adjustment of the outside fastening receiving throats 18 and 20 into alinement with the laterally adjusted positions of the outside shear blocks 2 and 4 on their bracket 8 or toward or away from the center throat block 22, the outside throat block carriers 24 and 26 are provided with threaded lugs 34 which receive the respective ends of a left and right hand screw threaded spindle 36 which is fixed against endwise movement in a lug 38 on the center throat block carrier 40. The milled head 41 on one end of the spindle 36 provides means for rotating the spindle and thereby effecting a simultaneous and uniform lateral adjustment of the outside throat blocks 18 and 20.

Three drivers 45, 46 and 48 are provided to drive the fastenings which are severed by movement of the passages 27 of the throats 18, 20 and 22 out of alinement with the wire receiving passages 14 and 16 in the shear blocks 2, 4 and 6 subsequent to the feeding of the wire through the passages 14 and 16 of the blocks 2, 4 and 6 into the passages 27. The outside drivers 45, 46 are carried respectively by driver bars 42, 43 which are also disposed laterally of the machine and are carried by a projecting bracket 50 vertically movable in guides in the head 3 and having a portion 52 projecting downwardly to constitute a driver bar 44 for the center driver 48.

Each of the two outside driver bars 42 and 43 has a tongue and slot connection 54 with the driver bar carrying bracket 50 for adjustment of the drivers 45, 46 transversely of the line of feed of the work and into correspondence with the outside shear blocks 2, 4 and the outside throat blocks 18, 20. Set screws 55 clamp the driver bars in their adjusted positions.

A uniform relative adjustment of the driver bars on the driver bracket 50 is effected simultaneously by means of a left and right hand screw threaded spindle 56 which is carried by the center driving bar 44 and has its ends received in threaded recesses in each of the outside driver bars 42 and 43. A set nut 58 is provided on the said spindle.

In order to allow corresponding fastenings of the several rows to be inserted in lines at an angle to the direction of feed of the work, or at a definite angular relation to the longitudinal median line of the shoe as, for example, to adapt the machine for left and right shoes, provision is made for offsetting the outside drivers 45, 46 at either side of the center driver 48, that is, with one driver set forwardly in the direction of feed of the work, and the other outside driver rearwardly, and for reversing this arrangement when desired. In the preferred em-

bodiment of the invention, this is effected by providing each of the outside driver bars 42, 43 with two recesses 60 for receiving the shank of the driver, one of the recesses 60 in each driver bar being located in a horizontal line passing through the shank of the center driver and the other recess being located forwardly or rearwardly of such horizontal line.

10 Thus with this arrangement the three drivers 45, 46, 48, may be held in their respective driver bars so as to form lines angularly disposed to the direction of feed of the work. Set screws or other appropriate 15 devices may be provided for clamping the drivers in the recesses in which they are inserted. By reason of the two wire receiving and driver passages 14 and 16 in each of the outside shear blocks 2 and 4, the shear 20 blocks 2 and 4 may be alined with the drivers in their different angular relations without any longitudinal adjustment of the shear blocks. When a change in the relative adjustment of the outside drivers 45, 46 and 25 the movable throat blocks 18 and 20 is desired in changing from rights to lefts, the end of the wire supply is transferred in each instance in the outside shear blocks 2 and 4 to the appropriate forward or rearward 30 passages to correspond to the wire receiving positions of the outside movable throat pieces 18 and 20 in their adjusted positions.

Preferably and as herein shown the machine has a single awl 62 in line with the 35 center driver inasmuch as it has been found that this arrangement permits the operator to make such changes of work position during the fastening inserting operation as are necessary to correct any tendency due to initial incorrect positioning of the work, for 40 example, for the rows of wire to run in a wrong direction relatively to the general contour of the work. This awl is carried by a block 64 which is mounted for adjustment 45 in the line of feed of the work upon a block 66 and is clamped in longitudinally adjusted position upon said block by the nut 68. The block 66 has at its forward end a laterally extending tongue 70 which is received 50 in the slotted lower end of the awl carrying bracket 72, this connection providing for a lateral adjustment of the awl 62. A set nut 74 clamps the block 66 in its adjusted position on the bracket 72.

55 The feed mechanism for the three strips of wire W comprises an inner feed roll 75 positively driven by a pawl and ratchet mechanism (not shown) and three outer rolls 76, 78, 80 mounted upon the forward 60 ends of plungers 82 which are pressed outwardly by springs not shown located in recesses in the plunger casings, all the rolls being carried by the sliding head 3. Preferably the driven feed roll 75 is made of

sufficient width to span the three wire supplies and the outer presser rolls 76, 78 are relatively adjustable into position to press upon the outer wires on the roll 75 in the positions in which they are located when laterally adjusted by threaded spindles 90 mounted on the ends of plungers 82 the lateral adjustment of the outside presser rolls being commensurated with the adjustments of the drivers 45, 46 and the throat blocks 18, 20. The plungers for the presser rolls 76, 78, 80 75 are each provided with a milled nut 92 for relieving the pressure on the wire so that the feeding of any of the wires may be suspended.

In the use of the machine as above described for three-row nailing, the space between the rows may be varied by adjusting the outside wire feed rolls 76, 78, the outside movable throat blocks 18, 20 and the drivers 45, 46 by rotating their respective spindles 80 90, 36 and 56 and by adjusting the outside shear blocks 2 and 4. In order to adapt the machine while working as a three-row slugger on right shoes for operation upon left shoes or vice versa, the operator changes the 90 outside drivers 45, 46 from one set of recesses 60 to the other set of recesses 60 in the driver bars; unclamps the outside movable throat blocks 18, 20 and after moving them longitudinally of the direction of feed 95 of the work into corresponding adjusted positions reclamps them to their carriers by means of the clamping bolts 21; and threads the two outside wires through the appropriate passages in the shear blocks 2, 4. It 100 will be appreciated that the construction as shown lends itself to the adjustment of the sets of fastening inserting instrumentalities to insert three rows of fastenings on a curve symmetrical with the line of feed of the 105 work and also convexly thereto, as illustrated in the drawings, it being obvious that if the machine were to be operated with the inserting instrumentalities adjusted in this manner the drivers would be correspondingly positioned in the recesses or holes in their support.

Having fully described my invention, what I claim as new and desire to secure by United States Letters Patent is:—

1. In a machine for inserting fastenings in boots and shoes, a plurality of sets of operating instrumentalities each comprising a driver for inserting a plurality of fastenings successively in a boot or shoe, a fastening receiving throat, and means for supplying successive fastenings to said throat for the operation of the driver, said sets of operating instrumentalities being organized to form substantially simultaneously a plurality of 120 rows of said fastenings, in combination with means for effecting a relative angular adjustment of said throats and said drivers of 125

the several sets to vary the relative angular arrangement of the fastenings of the several rows.

2. In a machine for inserting fastenings in boots and shoes, a plurality of sets of operating instrumentalities each comprising mechanism organized to insert a plurality of fastenings successively in a boot or shoe, said sets of operating instrumentalities being organized to form substantially simultaneously a plurality of rows of said fastenings, in combination with means for effecting a relative adjustment of corresponding instrumentalities of the several sets in the direction of the feed of the work to vary the relative arrangement of the fastenings of the several rows.

3. In a machine for inserting fastenings in boots and shoes, a plurality of sets of operating instrumentalities each comprising means adapted to insert a plurality of fastenings successively in a boot or shoe, said sets of operating instrumentalities being organized to form substantially simultaneously a plurality of rows of said fastenings, and the corresponding instrumentalities of the several sets being relatively adjustable to cause corresponding fastenings of the several rows to be inserted in lines at varying angles to the line of feed of the work.

4. In a machine for inserting fastenings in boots and shoes, a plurality of sets of operating instrumentalities each comprising mechanism organized to insert a plurality of fastenings successively in a boot or shoe, said sets of operating instrumentalities being organized to form substantially simultaneously a plurality of rows of said fastenings, in combination with means for effecting a relative angular adjustment of corresponding instrumentalities of the several sets to vary the relative angular arrangement of corresponding instrumentalities.

5. In a machine for inserting fastenings in boots and shoes, a frame, a head movably mounted on the frame, a plurality of sets of operating instrumentalities each comprising mechanism organized to insert a plurality of fastenings successively in a boot or shoe, and means carried by said head for feeding the work past said sets of operating instrumentalities to cause said instrumentalities to form substantially simultaneously a plurality of rows of said fastenings, certain of the corresponding instrumentalities of the several sets being carried by a common operating member movable on said head and being relatively adjustable to vary the distance between the rows of fastenings.

6. In a machine for inserting fastenings in boots and shoes, a frame, a plurality of sets of operating instrumentalities carried by said frame, each comprising fastening supplying means and fastening inserting mechanism mounted on said frame for ad-

justment independently of each other and organized to insert a plurality of fastenings successively in a boot or shoe, said sets of operating instrumentalities being organized to form substantially simultaneously a plurality of rows of said fastenings and certain of said fastening supplying means being constructed and arranged to deliver the fastenings selectively at different points, in combination with means for effecting adjustment of the fastening inserting mechanism of the set to which said fastening supplying means belongs conformable to the points of delivery of the fastenings, by said fastening supplying means.

7. In a machine of the class described, in combination, wire guiding means constructed and arranged to deliver the wire selectively at different points, mechanism constructed and arranged to receive the wire and to present a fastening formed therefrom in position for insertion into the work, means for adjusting said mechanism in accordance with the point of delivery of the wire by said wire guiding means, a driver for inserting the fastenings into the work, and means for effecting adjustment of the driver conformable to the adjustment of said mechanism.

8. In a machine of the class described, a frame, a head mounted for movement on said frame, means carried by said frame constructed and arranged to deliver fastenings selectively at different points, and fastening inserting mechanism carried by said head constructed and arranged to receive fastenings from the fastening supplying means and insert them into the work, said mechanism being adjustable conformably to the point of delivery of the fastenings.

9. In a machine for inserting fastenings in boots and shoes, a plurality of sets of operating instrumentalities each comprising, a driver for inserting a plurality of fastenings successively in a boot or shoe, a fastening receiving throat movable into and out of the line of drive of the fastenings, and means for supplying fastenings to said throat for operation thereon by said driver, said sets of operating instrumentalities being organized to form substantially simultaneously a plurality of rows of said fastenings, and said throats and drivers being carried by common operating members and being relatively adjustable to vary the distance between the rows of fastenings.

10. In a machine for inserting fastenings in boots and shoes, a plurality of sets of operating instrumentalities each comprising wire feeding mechanism, wire severing mechanism, and fastening driving mechanism organized to insert a plurality of fastenings successively in a boot or shoe, said sets of operating instrumentalities being organized to form substantially simultane-

- ously a plurality of rows of said fastenings, supporting means for each group of corresponding mechanisms of the several sets separate from the supporting means for the 5 other group, and means for adjusting the mechanism of each set of operating instrumentalities relatively to their supporting means to vary the relative arrangement of the fastenings of the several rows.
- 10 11. In a machine for inserting fastenings in boots and shoes, a plurality of sets of operating instrumentalities each comprising fastening supplying means and fastening inserting means, in combination with 15 an awl coöperating with one of said sets, and means for operating the awl to feed the work, corresponding operating instrumentalities of the several sets being adjustable to vary the relative arrangement of 20 the fastenings inserted by the several sets.
12. In a machine of the class described, in combination, a plurality of drivers each adapted to insert fastenings to form a row of fastenings, means for adjusting said 25 drivers relatively to each other, a plurality of mechanisms for presenting fastenings in position for insertion by said drivers, means for effecting adjustments of said mechanisms conformable to the adjustments of said 30 drivers and work feeding means comprising an awl operating to form an opening in the work for insertion of a fastening therein by one of said drivers.
13. In a machine of the class described, in 35 combination, a frame, a head movably mounted on said frame, an awl carried by the head and constructed and arranged to penetrate the work and feed the same upon movement of the head subsequent to the 40 work penetrating movement of the awl, a plurality of sets of fastening inserting instrumentalities carried by said frame, certain of said sets being constructed and arranged to insert fastenings in the openings 45 made by the awl, and means for adjusting corresponding instrumentalities of the several sets to vary the arrangement of the fastenings.
14. In a machine of the class described, a 50 frame, a head movably mounted on said frame, a driver carried by said head operable to insert fastenings into the work, an awl carried by said head operable to penetrate the work to form an opening to receive a fastening inserted by said driver and 55 operable by movement of said head while the awl is in the work to feed the work, means for adjusting said awl relatively to said driver in the direction of the feed of the work, and means for adjusting the awl 60 relatively to said driver in a direction transverse to the direction of feed of the work.
15. In a machine for inserting fastenings in boots and shoes, a frame, a head mounted 65 for movement on said frame, power-op-
- erated means for moving the head, a plurality of sets of operating instrumentalities each adapted to insert a plurality of fastenings successively in a boot or shoe and comprising drivers carried by the head 70 and throats also carried by the head for presenting fastenings to the drivers the several sets of operating instrumentalities being organized to form substantially simultaneously a plurality of rows of said fastenings, and means for effecting relative adjustment of corresponding instrumentalities of the several sets to vary the relative arrangement of the fastenings of the several 75 rows.
16. In a machine for inserting fastenings in boots and shoes, a frame, a head mounted for movement on said frame, a plurality of sets of operating instrumentalities each comprising means adapted to insert a plurality of fastenings successively in a boot or shoe, certain of the instrumentalities of each set being carried by said frame and certain other of the instrumentalities of each set being mounted for movement with 80 said head, the several sets of operating instrumentalities being organized to form substantially simultaneously a plurality of rows of said fastenings, in combination with means for effecting substantially 85 simultaneously a relative adjustment of certain of the corresponding instrumentalities of the several sets to vary the relative arrangement of the fastenings of the several 90 rows.
17. In a machine of the class described, in combination, a frame, a head movably mounted on said frame, a plurality of fastening inserting mechanisms each adapted to insert a plurality of fastenings successively to form a row of fastenings carried by said head, means for adjusting said 95 mechanisms relatively to each other, a plurality of means carried by the frame for supplying fastenings to said fastening inserting mechanisms for insertion into the work, and means for effecting adjustments of said fastening supplying means conformable to the adjustments of said fastening inserting mechanisms to vary the arrangement of the fastenings of the several 100 rows of fastenings.
18. In a machine for inserting fastenings, in combination, a frame, a head movably mounted on said frame, a plurality of drivers carried by said head, means for adjusting said drivers relatively to each other in a direction substantially transverse to the direction of feeding movement of the work, a plurality of mechanisms carried by said 105 head constructed and arranged to present fastenings in position for insertion into the work by said drivers, means for effecting adjustments of said mechanisms conformable to the adjustments of said drivers, and 110
- 120
- 125
- 130

means carried by said frame for supplying fastenings to said fastening presenting mechanisms.

19. In a machine for inserting fastenings in boots and shoes, a plurality of sets of operating instrumentalities each comprising means adapted to insert a plurality of fastenings successively in a boot or shoe, another set of such operating instrumentalities disposed to form a row of fastenings intermediate between the rows formed by said first mentioned sets, said sets of operating instrumentalities being organized to form substantially simultaneously a plurality of said rows, and means for adjusting said first named sets angularly with relation to said intermediate set to vary the arrangement of the fastenings of the several rows.

20. In a machine for inserting fastenings in boots and shoes, a frame, a head mounted for movement on said frame, a plurality of sets of operating instrumentalities each comprising means adapted to insert a plurality of fastenings successively in a boot or shoe, another set of such operating instrumentalities disposed to form a row of fastenings intermediate between the rows formed by said first mentioned sets, certain of the instrumentalities of each set being carried by said frame and certain other of said instrumentalities being mounted for movement with said head, and said sets of operating instrumentalities being organized to form substantially simultaneously a plurality of said rows, and means for jointly adjusting certain of the instrumentalities of said first named sets relatively to the corresponding instrumentality of said intermediate set to effect a predetermined relative arrangement of the fastenings of the several rows.

21. In a machine of the class described, in combination, a plurality of drivers each adapted to insert fastenings successively to form a row of fastenings, a driver intermediate between said first-mentioned drivers, means common to said first-mentioned drivers for adjusting said drivers relatively to said intermediate driver, a plurality of mechanisms constructed and arranged to present fastenings successively in position to be inserted by said drivers, and means for effecting adjustments of said mechanisms conformable to the adjustments of said drivers to vary the relative arrangement of the fastenings of the several rows of fastenings.

22. In a machine of the class described, in combination, a plurality of drivers each adapted to insert fastenings successively to form a row of fastenings, means for adjusting said drivers relatively to each other, a plurality of mechanisms constructed and arranged to present fastenings in position to be inserted by said drivers, and means for

effecting adjustments of said mechanisms conformable to the adjustments of said drivers to vary the relative arrangement of the fastenings of the several rows of fastenings.

23. In a machine of the class described, in combination, a plurality of drivers each adapted to insert fastenings successively to form a row of fastenings, means for adjusting said drivers relatively to each other, a plurality of throats constructed and arranged to present fastenings successively in position to be inserted by said drivers, and means for effecting adjustments of said throats conformable to the adjustments of said drivers to vary the relative arrangement of the fastenings of the several rows of fastenings.

24. In a machine of the class described, in combination, a plurality of wire guiding members, means for adjusting said members relatively to each other, a plurality of throats arranged to receive the wires from said wire guiding members and movable relatively to said wire guiding members to form fastenings from the wires by severance of the projecting ends of the wires and constructed and arranged to present the fastenings in position for insertion in the work, means for effecting adjustments of said throats conformable to the adjustments of the wire guiding members, a plurality of drivers each adapted to insert a plurality of fastenings successively to form a row of fastenings, and means for effecting adjustments of the drivers conformable to the adjustments of the wire guiding members and the throats to vary the relative arrangement of the fastenings of the several rows.

25. In a machine of the class described, in combination, a plurality of wire guiding members, certain of said members being constructed and arranged to deliver the wire selectively at different points, a plurality of mechanisms constructed and arranged to form fastenings from the wires and to present said fastenings in position for insertion into the work, said mechanisms being adjustable independently of the wire guiding members conformably to the points of delivery of the wires by the wire guiding members, and a plurality of drivers for inserting the fastenings into the work, said drivers being adjustable independently of the wire guiding members conformably to the adjustments of said fastening presenting mechanisms.

26. In a machine of the class described, in combination, a plurality of wire guiding members, certain of said wire guiding members being provided with a plurality of passages in any of which the wire may be selectively positioned, a plurality of throats each having a passage formed therein for receiving the wire from said guiding members, said throats being constructed and arranged

to form fastenings from the wires and to present said fastenings in position for insertion into the work and certain of said throats being adjustable to aline the passage 5 in the throat when in wire receiving position with either of the passages in the wire feeding means, a plurality of drivers for

inserting the fastenings into the work, and means for effecting adjustments of the drivers conformable to the adjustments of the 10 throats.

In testimony whereof I have signed my name to this specification.

THOMAS BRIGGS.
